HOUSTON, TEXAS

WELL DRILLING APPARATUS

Application filed February 24, 1928. Serial No. 256,539.

This invention relates to new and useful improvements in a well drilling apparatus.

One object of the invention is to provide a novel apparatus for drilling wells by the 5 cable tool process.

In drilling wells, particularly oil wells, by either the rotary process, or the cable tool process, as at the present time practised, formation is frequently encountered, in a 10 bore, which the drilling apparatus being used is not adapted to drill through.

In drilling a hole when formation of a wet or caving nature is encountered ordinary cable tools are not suitable for drilling 15 through such formation, and when hard formation is encountered rotary drilling machinery is not well adapted for drilling such hard formation, and inasmuch as both formations usually exist in the majority of wells it is very difficult to drill a well using either the cable tool process or the rotary process alone, 20 as these processes are at the present time practised. One of the main objects of this invention is to provide an apparatus of the character 25 described embodying the combination of cable tools with the ordinary rotary drill stem, or pipe, and wherein provision is made for forcing fluid through the bit to wash away the heavy formation, or "gumbo", as well as the cuttings, from the bit, as in rotary 30 drilling, and at the same time drilling either hard or soft formations, as encountered and preventing the walls of the bore from caving by the use of hydrostatic pressure, or by 35 plastering the walls of the bore by forcing into said walls mud laden fluid, as is commonly done in rotary drilling.

Another object of the invention is to provide an apparatus of the character described 40 wherein provision is made for the use of air, gas, or similar fluid to blow the cuttings away from around the drill bit, and out of the hole, in case it is advantageous to drill the hole dry, as in cavernous formations, or wherever 45 the use of water would cause the hole to cave or is not desirable or practical, or where it may be desirable to clean out a well, that has been producing, by the use of gas or air.

Another object of the invention is to provide an apparatus of the character described 50

of such construction that a change may be readily made, by the operator, from the cable tool process to the rotary process, and vice versa.

A further feature of the invention is to 55 provide an apparatus of the character described whereby the cable tool process of drilling may be efficiently prosecuted where water or other fluid is encountered, the apparatus being of such construction as to keep 60 the mud and cuttings away from the bit at all times, thus permitting the bit to work more efficiently and eliminating the necessity of bailing the cuttings from the bore.

With the above and other objects in view 65 this invention has particular relation to certain novel features of construction, operation and arrangement of parts an example of which is given in this specification and illustrated in the accompanying drawings, where- 70 in:

Figures 1, 2 and 3 show respectively, upper, intermediate and bottom sections respectively, shown in order from above downwardly, 75 showing the preferred form of the complete apparatus, the bottom section being shown partly in side elevation and the other sections being shown in vertical sectional views, and the operating cable being shown connected to the drilling tool.

Figure 4 shows a bottom end view of the apparatus.

Figures 5, 6 and 7, respectively, show vertical sectional view of the upper, intermediate and lower sections, taken in order from top 85 to bottom of another form of the apparatus.

Figure 8 shows a transverse sectional view taken on the line 8—8 of Figure 1.

Figure 9 shows a transverse sectional view taken on the line 9—9 of Figure 2.

Figure 10 shows a transverse sectional view taken on the line 10—10 of Figure 2.

Figure 11 shows a cross sectional view taken on the line 11—11 of Figure 5.

Figure 12 shows a cross sectional view 95 taken on the line 12—12 of Figure 1.

Figure 13 shows a cross sectional view taken on the line 13—13 of Fig. 6, and

Figure 14 shows an inside view of a cable 100 engaging slip employed.

Referring now more particularly to the drawings, wherein like numerals of reference designate similar parts in each of the figures, the numeral 1 designates a drill stem, or pipe, 8 which has an inwardly thickened coupling 2, near its lower end with a plurality of water courses 3 extending from the upper to the lower end thereof. Attached to the lower end of the stem 1 there is a shoe 4 whose lower 10 end is outwardly flared. The numeral 5 designates a cable tool drill bit which has a fluid course 6 extending axially therethrough down near the cutting edge 7, of the bit and there separates into the branches 8, 8 which 15 terminate in the vertical channels 9, 9 on opposite sides of the bit. The cutting edge 7 of the bit is longer than the outside diameter of the stem, or pipe 1 to which the bit is attached. The bit has an extended shank 10 which fits 20 up within the lower end of the stem 1, extending through the shoe 4. There is a suitable packing ring 11 within the shoe and around the shank 10 which is retained in place by a surrounding annular channel 12 25 which is seated in said shoe and in whose inside channel the packing 11 is retained. Around the upper end of the shank 10 there is another packing ring 13 which is seated on the retainer ring 14 carried by said shank. 30 The packings 11 and 13 prevent air, gas, or other fluid used from passing between the bit shank and drill stem and force said fluid to pass through the fluid course 6 in the bit. A solid stem 15 is connected to the upper end of 35 the shank 10. This stem is formed of sections connected by the joint 16. Beneath said joint the stem 15 has a relatively thick surrounding collar 17 screwed thereon, and provided with vertical channels 18 and the lower 40 end of the stem 15 has the channels 19 which converge from the outside of said stem 15 and unite in the fluid course 6.

Around the lower section of the stem 15 there is a sleeve 20, which is spaced from said 45 stem 15 and has an external undercut flange 21, at its upper end. Around this sleeve 20 there is an annular yieldable cushioning member 23 whose lower end is seated in an inside annular seat 24, of the inwardly thickened collar 25, which connects sections of the 50 drill stem 1. The flange 21 seats on the upper end of the member 23. A cushioning device is thus provided. When the drill drops, the collar 17 may strike against the top of the 55 sleeve 20 but the jar will be broken by said cushioning device. This will only occur in case the bore deepened faster than the pipe 1 is lowered.

Attached to the upper end of the stem 15 60 there is a tubular support 26, whose upper end is internally threaded and screwed into said upper end there is a tubular guide 27 having the internal annular downwardly facing shoulder 28. Above said shoulder the 65 guide is outwardly flared, as at 29 and lead-

ing through this flared portion and through the support 26 are the fluid channels 30. Beneath the shoulder 28 the guide is flared or tapered downwardly at 31.

Located within the lower end of the support 26, and connected to the upper end of the stem 15 by means of the stud bolt 32 there is a cylindrical anchor block 33 having an integral upwardly extending guide tube 34 whose upper end is outwardly flared and has a bearing ring 35 screwed therein. There is a lengthwise bore 36 extending from the upper end of the tube 34 and continuing on down through the block 33 and whose lower end is reduced forming a seat 37 for the conical shaped head 38 carried by the lower end of the rod 39. The upper end of this rod is connected to the solid head 40, hereinafter described, and a coil spring 41 surrounds said rod 39 and is interposed between the bearing ring 35 and the head 40. The lower end of said rod 39 works through the bearing ring 35 and through the bore 36. The anchor block 33 has the oppositely disposed, aligned, vertical slots 42, 42 in which are located the radially movable blades 43, 43. These blades have the transverse bearings 44, 44 provided to receive the bearing pins 45, 45 whose ends are anchored to the anchor block 33. The lower ends of the blades are beveled inwardly as at 46, 46 and interposed between said lower ends is the push spring 47. The upper ends of said blades have the inwardly projecting, downwardly facing shoulders 48, 48.

Above the anchor block 33 and surrounding and spaced from the tube 34 there is a clamp sleeve 49 whose upper end is outwardly flared and secured to opposite sides of this clamp sleeve are the keys 50, 50, which work in the vertical slots, or keyways, 51, 51, in the tubular support 26.

There are the elongated slips 52, arcuate in cross sectional contour and preferably three in number. These slips are arranged around and are seated in the arcuate notches 53 of the head 40, and have the side notches 54, 54, which form the opposing upper and lower shoulders 55 and 56, said notches 54 receiving the vertical ribs 57 on the out-side of the head 40, between the slots 53, and the shoulders 55, 56, engaging the upper and lower ends, respectively, of the adjacent ribs 57 to prevent the endwise movement of the slips 52 relative to the head 40. Screwed on the head 40, and surrounding said slips 52, there is a ring nut 58 which retains the slips against displacement from the head 40, and this nut is secured against unscrewing from the head by means of a set screw 59. The lower ends of the slips 52 diverge outwardly and are downwardly tapered, and are inwardly beveled as at 60 and within said lower ends, and secured thereto there is a yieldable expander ring 61, preferably of rubber.

When the apparatus is in position to operate the upper ends of the slips 52 abut the inside, annular, downwardly facing shoulder 28 of the guide 27. Beneath their upper 5 ends the slips 52 have the inside downwardly facing shoulders 63.

The numeral 64 designates a shaft preferably formed of steel whose lower end has a head 65, adapted to engage under the shoulders 63 and to the upper end of which the operating cable 66 is connected by means of the conventional swiveling rope socket 67.

In assembling the apparatus, preparatory to letting it down into the bore the slips 52 are first fitted into the slots 53 of the head 40 and the ring nut 58 is then screwed onto said head over said slips and secured in place by the set screw 59. The expander ring 61 is then secured within the lower ends of said 20 slips. The clamp sleeve 49 is then fitted over the tube 34 the ring nut 35 is fitted onto the rod 39 and screwed into the upper end of the tube 34. The spring 41 is then fitted over the rod 39 and the upper end 25 of this rod is then screwed into the head 40. This assembly is then inserted, from the bottom, up into the tubular support 26. During this operation the blades 43 can be moved inwardly to permit them to enter the bottom 30 of the tubular support 26 and when they move up into registry with the opposing vertical slots 68, 68 cut through the support 26 they will be forced outwardly through said slots by the pressure of the spring 47. 35 The keys 50, 50 can then be inserted through the keyways 51, 51 and into the dovetailed grooves, 69, 69 of the clamp sleeve 49 and braded, or welded, therein or secured therein in any desirable manner. The stud bolt 32 40 may then be attached to the anchor block and the upper end of the stem 15 then screwed up into the lower end of the tubular support 40 and onto said stud bolt 32.

The sleeve 20 is fitted over the stem 15 or 45 in the forms shown in Figures 5 and 9, is mounted on stem 15' in longitudinal half sections which may be welded together in making the assembly, and the cushioning member is then fitted around it and the lower 50 parts of the drill stem and associated parts, including the packings are then assembled in an obvious manner.

The drill is suspended in the drill stem 1 by the external collar 17 of said drill stem, 55 resting on the upper end of the sleeve 20, with the drill bit 5 below the shoe 4.

The shaft 64 has not yet been lowered into the drill stem so the upper ends of the slips 52 are held within the guide 27 by the pressure of the spring 41.

The apparatus, assembled as above described may now be let down into the well bore. When the drill 5 is on the bottom of the bore the cable 66 may be attached to the 65 shaft 64 and said shaft let down through the

drill stem 1 until its head 65 contacts against the upper ends of the slips 52. The weight of the shaft 64 will force said slips downwardly, compressing the spring 41, and forcing the upper ends of said slips out of the guide 27 and the head 65 will spread the upper ends of said slips and pass beneath the slip shoulders 63. The spring 41 will now operate to carry the slips 52 back up into the guide 27 which will force said upper ends together so as to carry the shoulders 63 into interlocking relation with the head 65 when the rod 64 is elevated through the cable 66. The cable 66 is thus locked to the drilling tool ready for drilling operations. The cable is now alternately lifted and released, by the conventional mechanism at the ground surface provided for the purpose and the bit 5 is correspondingly lifted and dropped against the bottom of the bore. Meanwhile water may be forced down through the drill stem 1 and the various fluid channels described, by a pump at the ground surface, to flush away the cuttings from the bottom of the bore, or air or gas may be forced down, by suitable apparatus for the purpose, to carry away said cuttings in case it is desired to drill the well dry.

The apparatus should be so located in the bore that the bit 5 will operate against the bottom of the bore without the collar 17 striking the upper end of the sleeve 20, the shock absorber arrangement being provided to absorb the shocks in case the apparatus is so located in the bore that said collar 17 might contact against said absorber.

When it is desired to detach the line 66, from the drill, the drill 5 is set on bottom and the line 66 is slackened to permit the shaft 64 to move downwardly until its lower end rests on the head 40 and forces said head 40 and the slips 52 downwardly. The rod 39 is forced down between the blades 43, 43 with its head 38 engaged under the shoulders 48, of said blades and with the spring 41 under compression, the pipe 1 meanwhile being elevated so that the inwardly thickened coupling 2 will pass over the blades 43 and hold them inwardly in locking relation with the head 38, thus holding the head 40 in its said lowered position. The drill pipe 1 is moved further upwardly, the inwardly thickened coupling 2 engaging the keys 50 and forcing the clamp sleeve 49 upwardly over the lower 110 ends of said slips 52 thus contracting said ends and spreading the upper ends of the slips. The upward movement of the clamp sleeve is stopped by the flange 21 coming into contact with the lower end of the collar 17. The rod 64 is thus released from the slips 52 and the cable 66, with said rod attached may be withdrawn from the drill stem 1, as will sometimes be necessary. When drilling

is to be resumed the cable may be re-connected to the drilling tool in an obvious 125 130

manner, that is, the stem which is lowered and the coupling 2 releases the keys 50 permitting the clamp sleeve 49 to descend and release the lower ends of the dogs 52. As 5 the coupling 2 further descends it will release the blades 43 permitting them to spread and the shoulders 48 will release the head 38 and thereupon the spring 41 will operate through the rod 39 to move the head 40 and 10 its appendants upwardly into the position shown in Figure 1. The shaft 64 may then be lowered and its head 65 will then engage the upper ends of the dogs 52 and force the dogs downwardly and their upper ends outwardly until the head 65 passes between the upper end of said dogs and beneath the shoulders 63 thereof. The spring 41 will thereupon force the head 40 and dogs 52 upwardly and the upper ends of said dogs will be contracted by the upwardly tapering guide 27 causing the shoulders 63 to contract into position to engage the head 65 upon upward movement of the shaft 64.

A slightly modified form of the device is 25 shown in Figures 5 to 7 inclusive. In this form the slips 52' are inverted and are anchored to the head 40' in the same manner as illustrated and described in connection with Figures 1 and 2. In this form the ring nut 58' 30 has the radial keys 71, 71, which work in the vertical slots 72, 72, of the tubular support 26'. The upper end of the tubular support 26', is connected to the lower end of the shaft 64' which, in turn is suspended from 35 the cable 66, being connected thereto by the conventional swiveling rope socket 67.

Within the upper end of the tubular support 26' there is a weight 73 having an elongated depending neck 74 whose lower end 40 rests on the head 40' and is held centered thereon by the upstanding projection 75 which enters the socket 76 in the lower end of said neck. The weight works through an annular guide 77 secured in the support 26'. The 45 expander ring 61, in this form is located within, and attached to the upper end of said slips 52' as shown in Figure 6. Within the lower end of the support 26' is secured the tubular guide 27' having the internal 50 upwardly facing shoulder 28'. Beneath said shoulder the guide is downwardly flared, as at 29'. Above the shoulder 28' the guide is flared, or tapered, upwardly, as at 31'. There is a hanger rod 78 whose upper end 55 has an enlarged head 79 and whose lower end works through the upwardly extended sleeve 80, formed integrally with and extending upwardly from the nipple 81. The coupling 82 connects the nipple 81 to the stem 15'. 60 Within the coupling 82 there is a nut 83 secured on the lower end of the rod 78 and a coil spring 84 surrounds the rod 78 and is interposed between the nut 83 and the nipple 81.

65 While the apparatus is in operation the

head 79 is engaged by the inside shoulders 63' of the slips 52' and the lower ends of said slips are in abutting relation with the shoulder 28', said slips being held in engagement with the head 79 by means of the guide 27'. 70 As the cable 66 is operated the drilling tool 5 will be alternately lifted from and dropped against the bottom of the bore in the usual way.

In this form of the device the drilling tool 75 5' and the stem 15' to which it is connected, and the co-operating parts of the drill stem 1 are substantially similar to the form shown in Figures 1 to 3 inclusive, the integral shoulders 17' performing the function of the collar 17.

In use the drilling tool, of this modified form, is assembled, in an obvious manner, with the drill stem and said stem is then let down into the bore, without the cable 66 and 85 its appendants, which includes the tubular support 26' and the parts connected thereto. Said cable and its said appendants, may then be lowered until the head 79 contacts with and stops the downward movement of the slips 52' and the guide sleeve 27' will move on downwardly releasing the lower ends of said slips and permitting said ends to spread and pass down over said head 79 and the shoulders 63' to engage under said 90 head when the cable is pulled upwardly. The cable is thus connected to the drilling tool 95 and the apparatus is then ready for operation.

When it is desired to detach the cable 66, in this form of the apparatus, the cable is 100 released to permit the tubular support 26' to move downwardly and the inwardly thickened coupling 2 will engage the keys 71 and thus hold the head 40' and the slips 52' against downward movement, and the flared lower end of the guide 77 will engage over and the upper ends of the slips 52' and force said ends inwardly and their lower ends outwardly so that the shoulders 63' will release the head 79 and the cable with its appendants may be then withdrawn from the stem 1. 105

While I have shown what I now consider the preferred forms of the invention it is obvious that mechanical changes may be made therein and equivalents substituted for the parts shown and I hereby reserve the right to make such alterations, substitutions and modifications as may be found desirable so long as I do not depart from the principle of the invention as comprehended within 110 the scope of the appended claims.

What I claim is:—

1. The combination with a tubular drill stem, of a reciprocable drilling tool at the lower end of the stem, an operating cable extending from the ground surface down through the stem and connected to said tool and means operable by the stem and effective to release said cable from said tool. 125

2. The combination with a tubular drill 130

- stem, of a reciprocable drilling tool at the lower end of the stem, an operating cable extending from the ground surface down through the stem and connected to said tool, 5 said tool having a fluid course therethrough, a cushioning device interposed between said tool and stem, and packing disposed around the tool and between said tool and the drill stem.
- 10 3. The combination with a tubular stem, of a reciprocable cable drilling tool at the lower end of the stem, a flexible line extending down through said stem, from its upper end, releasable interlocking means carried by the 15 lower end of said line and the upper end of said tool, respectively through which the line may be connected to or detached from said tool.
- 20 4. The combination with a tubular stem, of a reciprocable cable drilling tool at the lower end of the stem, a flexible line extending down through said stem, from its upper end, releasable interlocking means carried by the 25 lower end of said line and the upper end of said tool, respectively through which the line may be connected to or detached from said tool while the apparatus is in the well bore.
- 30 5. The combination with a tubular stem, of a reciprocable cable drilling tool at the lower end of the stem, a flexible line extending down through said stem, from its upper end, releasable interlocking means carried by the lower 35 end of said line and the upper end of said tool, respectively through which the line may be connected to or detached from said tool, said interlocking means permitting the relative rotation of the interlocked parts.
- 40 6. The combination with a tubular stem, of a reciprocable cable drilling tool at the lower end of the stem, a flexible line extending down through said stem, from its upper end, releasable interlocking means carried by the lower 45 end of said line and the upper end of said tool, respectively through which the line may be connected to or detached from said tool, said tool having a fluid channel extending therethrough, through which fluid may be forced, from said stem, to the bottom 50 of the bore.
- 55 7. The combination with a tubular stem, of a reciprocable cable drilling tool at the lower end of the stem, a flexible line extending down through said stem, from its upper end, releasable interlocking means carried by the lower 60 end of said line and the upper end of said tool, respectively through which the line may be connected to or detached from said tool, said tool having a fluid channel extending therethrough, through which fluid may be forced, from said stem, to the bottom of the bore, and means between the tool and stem to prevent the passage of fluid downwardly between said tool and stem.
- 65 8. The combination with a tubular drill stem of a cable drilling tool at the lower end of the stem, a flexible operating line extending down through the stem from the upper end thereof, said drilling tool and line being provided, one with a shaft having an enlarged head, and the other with releasable interlocking means adapted to engage said head to effect the connection of said line to said tool. 70
9. The combination with a tubular drill stem of a cable drilling tool at the lower end of the stem, a flexible operating line extending down through the stem from the upper end thereof, said drilling tool and line being provided, one with a shaft having an enlarged head, and the other with releasable interlocking means adapted to engage said head to effect the connection of said line to said tool, means for disengaging said interlocking means from said head. 75
10. The combination with a tubular drill stem of a cable drilling tool at the lower end of the stem, a flexible operating line extending down through the stem from the upper end thereof, said drilling tool and line being provided, one with a shaft having an enlarged head, and the other with releasable interlocking means adapted to engage said head to effect the connection of said line to said tool, means for disengaging said interlocking means from said head, and means for holding said interlocking means in said disengaged relation to permit the detachment of said line from said tool. 80
11. The combination with a tubular stem, of a cable type drilling tool at the lower end of the stem, said tool and stem being provided with opposing abutments spaced to permit a limited reciprocatory movement of the tool relative to the stem. 85
12. The combination with a tubular stem, of a cable type drilling tool at the lower end of the stem, said tool and stem being provided with opposing abutments spaced to permit a limited reciprocatory movement of the tool relative to the stem, some of said abutments being yieldable to form shock absorbers. 90
13. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 95
14. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem 100
15. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 105
16. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 110
17. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 115
18. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 120
19. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 125
20. The combination with a tubular stem, of a cable type drilling tool at the lower end of the stem, said tool and stem being provided with opposing abutments spaced to permit a limited reciprocatory movement of the tool relative to the stem, there being a fluid channel leading from within the stem down through said tool through which fluid may be forced from within the stem to the bottom of the bore. 130

down through said tool through which fluid may be forced from within the stem to the bottom of the bore, and means preventing the passage of fluid downwardly between the stem and tool.

15. The combination with a tubular drill stem, which includes a tubular shoe at the lower end thereof, of a drilling tool working through said shoe and reciprocable with respect thereto, and packing within said shoe around said tool, means connected to the tool and extending up through the stem and operable from the upper end of the stem through which the tool may be reciprocated, and releasable interlocking means connecting said reciprocating means to said tool.

16. In well drilling apparatus a tube adapted to be lowered into a well bore, a drilling tool support reciprocable in the tube, a drilling tool at the lower end of said support and working beneath the lower end of the tube, an annular packing element which fits closely within the tube and surrounds and is mounted on and moves with said support, said support having a fluid channel downwardly therethrough whose upper end communicates with the interior of said tube above said packing element and through which channel fluid may pass from the interior of the tube into the bore beneath said tube and a flexible line through which said tool support may be suspended.

17. In a well drilling apparatus a tube adapted to be lowered into a well bore, a drilling tool support reciprocable in the tube, a drilling tool attached to said support and working beneath the lower end of the tube, an annular cup shaped packing which fits closely within the tube and surrounds and is mounted on and moves with said support, said support having a fluid channel downwardly therethrough whose upper end communicates with the interior of said tube above said cup shaped packing and through which channel fluid may pass from the interior of the tube into the bore beneath said tube and a flexible line through which said tool support may be suspended.

18. In testimony whereof I have signed my name to this specification.

REDUS D. DODDS.
